UNITED STATES PATENT OFFICE

JOHN C. WOLFF AND FRED POKALL, OF FORBES, NORTH DAKOTA

RAIL CLAMPING CHAIR

Application filed February 10, 1931. Serial No. 514,818.

This invention relates to rail chairs for railroad rails and the general object of the invention is to provide a chair which is so constructed as to hold the rail to the chair without the necessity of driving spikes to engage the flanges of the rail to hold it to the tie, the rail chair itself being spiked to the tie.

A further object of this invention is to provide a chair of this character which is so constructed that the rail can be removed without the necessity of pulling spikes from the ties, thus very greatly lengthening the life of the tie by preventing the tie from becoming "spike killed" due to the withdrawal and redriving of spikes and decay of the wood consequent on water collecting in old spike holes.

A further object is to provide a construction of this character in which the chair is made in three parts, which when engaged with each other, engage over the flange of the rail and prevent the rail from being lifted up, the construction being such, however, that the rail may slide longitudinally within the chair to thus permit the rail to expand and contract and further the construction being such that upon the longitudinal withdrawal of one of the pieces of the chair, the second piece may be removed from the main body of the chair and then the rail may be lifted up on one side and shifted out of position within the chair.

A further object is to provide a device of this character which will secure a relatively long bearing of the rail on the tie and a much larger bearing than if the rail rested directly on the tie, thus preventing the rail from wearing a channel in the tie which it usually does where rails are spiked directly to the tie.

Another object is to provide a construction of this character which will tend to hold the ties parallel to each other.

Other objects will appear in the course of the following description.

Our invention is illustrated in the accompanying drawings, wherein:

Figure 1 is a top plan view of a rail and rail chair constructed in accordance with our invention;

Figure 2 is a bottom plan view thereof;

Figure 3 is an end elevation of our improved chair, the rail being in section;

Figure 4 is a section on the line 4-4 of Figure 1;

Figure 5 is a section on the line 5-5 of Figure 3;

Figure 6 is a top plan view of the chair assembled, but with the rail removed;

Figure 7 is a top plan view of the main body of the chair partly in section;

Figure 8 is a top plan view of one of the removable chair sections;

Figure 9 is a bottom plan view of the other removable chair section.

Referring to these drawings, 10 designates the main body of the chair which may be made of cast metal, as for instance, cast iron or steel. This chair is formed with a longitudinally extending channel 11 within which the rail is disposed, the channel being defined on the outside of the rail by an upstanding vertical wall 12 and on the inside of the rail by the vertical wall 13 and the overhanging flange 14. Outward of the walls 12 and 13, the ends of the chair are beveled downward and provided with spike openings 15, through which spikes may be driven into the tie to hold the chair firmly upon the tie. Preferably the under face of the chair is grooved, both longitudinally and transversely, in order that it may secure a firm adherence to the tie. The channel 10 is formed adjacent one edge face of the chair with a depressed portion 16 having an area approximately one quarter of the area of the channel.

At the center of this depression 16 there is formed a further depression 17 having in actual practice a length of about one inch and a width of about one-half of an inch, this depression 17 being approximately one-quarter inch deep. Obviously these dimensions may be varied.

Coacting with the main body 10 of the chair is a plate 18 having a width at one end approximately equal to half the width of the channel, so that this end of the plate 18 may fit within the depression 16. This end of the plate is formed with a downwardly extend-

ing lug 19 fitting within the depression 17 and, therefore, locking the plate in the depression 16. When so put in place, this plate 18 has its upper face flush with the upper surface of the channel 11. The outer end of the plate is straight and formed at its outer end with the upwardly and inwardly extending flange 20 adapted to overhang the flange of the rail A. The opposite edge of the plate 18 is straight for a portion of its length as at 21 and then is cut in slightly at 22 and inclined longitudinally and between the flange 20 as at 23. Extending downward from this inclined edge is a longitudinal lug 24. This lug tapers toward its outer end.

Disposed to fit against the plate 18 is a plate 25 having a width at its inner end equal to half the width of the channel 10. The outer edge of this plate is formed with the overhanging flange 26 which engages over the flange of the rail and this flange is, of course, parallel to the length of the rail. The inner edge of the plate 25, however, is inclined at 27, this inclination being the same as the inclination of the lug 24 and of the edge 23 of plate 18.

Extending downward from this inclined edge 27 is a vertical wall 28 having an inclination corresponding to the inclination of the edge 27, and this wall 28, together with an opposing parallel wall 29 declines a slot or groove 30. Below the bottom of this slot or groove, the metal is extended downward as at 31 to a considerable distance. This downwardly extending head 31 is adapted to fit at its end against the side face of a tie. The under face of the plate 25 is formed with a longitudinally extending lug 32 which projects beyond the inner edge of the plate and constitutes a tenon adapted to enter a mortise 33 in the side edge face of the chair body 10.

In the use of this chair, the body of the chair is spiked to the tie by any of the standard spikes and when it is desired to place the rail on the chair, the plate 18 is put in place. The rail may then be slipped laterally into position until its inner flange is under the overhanging flanges 14 and 20 and then the edge of the opposite flange at the outer side of the rail will drop down into the channel 10 and abut against the wall 12. Then in order to lock the rail in place, the member 25 is slid longitudinally, the lug 24 on plate 18 fitting within the groove 30 with the flange 26 overhanging the outer flange of the rail. When the plate or member 25 has been forced fully home, the tenon 32 will enter the mortise 33, thus locking the member 25 to the main body of the chair. The lug 24 and slot 30 are not entirely vertical but inclined to the vertical so that it is impossible to draw upward on the rail and thus pull up the member 25. When it is desired to remove the rail, it is only necessary to slide the mem-

ber 25 off of the rail and out of its engagement with the lug 24.

This frees one edge of the rail which may then be pulled up until the flange is above the wall 12 when the rail may be readily lifted laterally and then upward until completely detached.

It is to be particularly noted and it is one of the features of our invention that the recess 17 and the lug 19 are disposed on a vertical slant so that the lug 19 may be said to be undercut on one edge face and the solid undercut on the like edge face. In actual practice the overhanging flange 14 is disposed on the inside of the rail, that is, between the rails. The flange on the car wheel in traveling on the inside of the rails has a tendency to push the top of the rail outward. In doing this, it may have a tendency to lift the rail on the inside edge, but by reason of the interlock caused by the slanting faces of the recess 19 and the lug 17, the recess and lug will interlock to overcome this tendency and prevent the inside of the rail from rising. This assists the flange 14, therefore, from resisting this lifting up tendency.

By reason of the fact that the lug 24 is inclined away from the flange 26 or member 25, it has a tendency to force the member 25 laterally when the member 25 is being slid off. As a consequence, this member 25 will not work off accidentally but must be driven off and driven on. The lug 24 is tapered for the purpose of permitting the plate 25 to be more easily driven in place. This longitudinal inclination of the lug 24 and the slot 30 impedes the longitudinal movement of the plate 25.

A downward extension 31 is provided to afford a solid portion on which to hammer or drive the part 25 into position. This must be done under the rail and by having this extension, it is much easier to drive the part 25 under the rail than it otherwise would be. This downwardly extending lug 24 furthermore abuts against the tie and thus aids in holding the tie straight. Furthermore by providing this extension, it is possible to drive a wedge or pinch bar between the extension 31 and the tie to remove the portion 25. The part 18 is formed as a separate piece and not integral with or cast on the main body 10 because if it were cast on the main body 10, it would be necessary to slide the rail into position under the flange 20 after 10 had been spiked to the rail and in case of a derailment of the wheels of the car, either the flange 20 or the flange 26 would be very likely to be broken off. If the part 18 were cast in one piece with the part 10, and either of the flanges 20 or 26 were broken off, it would then be necessary to replace the whole part 10 whereas if they are cast in two pieces, the part 18 is readily replaced and the part 10 can be used over again. By the use of this

device, it would be possible to use reinforced concrete ties and the main chair 10 may be bolted on the concrete tie by means of ordinary round bolts. These should be used in place of spikes and because the openings 15 would then be circular instead of square.

We claim:—

1. A rail chair of the character described, comprising a body having a rail channel defined on one side by a vertical wall and on the other side by an overhanging wall, a rail locking plate operatively engageable with the body upon longitudinal movement in one direction and having an overhanging flange 15 diagonally opposed to the overhanging flange on the body.
2. A rail chair of the character described, comprising a body having a longitudinally extending channel, the channel being defined 20 on one side by a vertical wall and on the other side by an overhanging wall, a plate having detachable interlocking engagement with the body, the upper surface of the plate forming a continuation of the upper surface 25 of the body and the plate extending longitudinally outward from one side face of the chair, said plate having an overhanging flange constituting a continuation of the overhanging flange on the body and a second 30 plate complementary to the first named plate and having an overhanging flange opposed to the overhanging flange on the first named plate, the second named plate having interlocking sliding engagement with the first 35 named plate and having a vertical member interlocking with the body when the second named plate has been shifted longitudinally against the body.
3. A rail chair comprising a body having 40 a longitudinally extending channel defined on one side by a vertical wall and on the other side by an overhanging wall, the upper face of the channel being recessed at one corner of the chair, the recess opening upon 45 the side face of the body, there being a consequent deeper recess extending downward from the bottom of the first named recess, a plate having one end adapted to fit in said first-named recess and having a lug on its 50 under face fitting within the second-named recess, said plate having its side edge adjacent its outer end formed with an overhanging flange constituting a continuation of the overhanging flange on the body, the opposite 55 edge of said plate at its outer end being longitudinally inclined and formed with a depending longitudinally extending inclined lug, and the second plate adapted to fit beneath the rail and opposing that portion of 60 the first named plate projecting beyond the body, the second named plate having on its outer edge an overhanging flange, the inner edge of the second-named plate being inclined complementary to the inclination of 65 the second named plate and being formed

with a depending portion having an inclined groove adapted to receive the inclined lug of the first named plate, the second named plate having a projecting tenon and the side face of the body having a mortise within 70 which said tenon may engage.

4. A rail chair comprising a body having longitudinally extending rail channel defined on one side by a vertical flange and on the other side by an overhanging flange, and 75 a plurality of separate complementary plates, each having a rail engaging overhanging flange, one plate having interlocking engagement with the body, the other plate having sliding interlocking engagement with the 80 first-named plate.

5. A rail chair comprising a body having a longitudinally extending rail channel defined on one side by a vertical flange and on the other side by an overhanging flange, 85 a pair of separate complementary plates, each having a rail engaging overhanging flange, these flanges being adapted when the plates are in position to align with the wall and flange of the body, the body on its upper 90 face having a recess and one of said plates having a lug engaging and interlocking with said recess against upward movement, the other plate having sliding engagement with the first named plate. 95

6. A rail chair comprising a body having a longitudinally extending rail channel defined on one side by a vertical flange and on the other side by an overhanging flange, and a pair of separate complementary plates, each 100 having a rail engaging overhanging flange, the face of the body on one side being recessed to receive a portion of one of said plates and said recess having a longitudinally extending recess in its bottom, the plate fitting 105 said recess having a lug extending into the second named recess, the lug and second named recess having interlocking engagement with each other against upward movement, said plate on its lower face having a 110 longitudinally extending depending elongated lug, the other plate on one edge having a depending portion formed with a recess slidingly engaging said lug, said last named plate having a tenon and the end face of the 115 body having a recess to receive said tenon.

7. A rail chair comprising a body having a longitudinally extending rail channel defined on one side by a vertical flange and on the other side by an overhanging flange, said 120 body adjacent the overhanging flange at one end of the body being recessed, the recess extending beneath the flange, the bottom of the recess having a transversely extending recess, a plate, one end of which is disposable 125 in said first-named recess, the bottom of the plate having a lug engaging in the second named recess and having interlocking engagement therewith against upward movement, said plate having on one side an over- 130

- hanging flange adapted when the plate is in place to aline with the overhanging flange on the body, said plate on its under face and along the edge opposite from said flange being formed with a longitudinally extending slightly inclined lug, a second plate adapted to be disposed against the end of the body and having at one edge an overhanging flange adapted to aline with the vertical flange of the body, the inner edge of the plate having a depending portion longitudinally curved to have sliding engagement with the depending lug on the other plate, said depending portion forming a driving head for the last named plate.
8. A rail chair comprising a body having a longitudinally extending rail channel defined on one side by a vertical flange and on the other side by an overhanging flange, a plate forming an extension of the body on that side of the body having a vertical flange, said plate having an overhanging flange alining with the vertical flange of the body, and means detachably engageable with the body for locking the plate in place.
9. A rail chair comprising a body having a longitudinally extending rail channel defined on one side by a vertical wall and on the other side by an overhanging flange, a plate having interlocking detachable engagement with the body and when in place projecting from one end thereof and having its upper face flush with the bottom of the channel, said plate having an overhanging flange along one edge, and a second plate having sliding engagement with the first plate and on its outer end having an overhanging flange alining with the vertical wall of the body when the second named plate is in place.
- 40 In testimony whereof we hereunto affix our signatures.

JOHN C. WOLFF.
FRED POKALL.
